UNITED STATES PATENT OFFICE

2,179,490

EDGE GAUGE FOR CHANNELING MACHINES

William R. Bolten, Chicago, Ill., assignor to
United Shoe Machinery Corporation, Borough
of Flemington, N. J., a corporation of New
Jersey

Application March 22, 1938, Serial No. 197,436

13 Claims. (Cl. 12—27)

This invention relates to improvements in gauging devices for shoe machines and is illustrated as embodied in an edge gauge mechanism suitable for use in a channeling machine intended for operating upon so-called orthopedic insoles.

Orthopedic insoles, so-called, are made with lateral extensions or wings at their inside shank portions or with extensions at both the inside and outside shank portions of the insoles, and in the manufacture of shoes having such insoles the extensions or wings are laid back or molded against the sides of the lasts so that they will serve in the finished shoes to support the arches of the feet.

Edge gauges of channeling machines are commonly adjustable to produce a feather of varying width. For example, the feather may be $\frac{1}{16}$ of an inch wide at the outside ball, $\frac{1}{16}$ of an inch at the toe and inside ball and $\frac{1}{16}$ of an inch at the shank; however, the adjustments provided for are of such relatively small variations of width that they cannot be used to care for the wide extensions to be encountered at the shanks of orthopedic insoles. Accordingly, some means must be provided for removing the edge gauge from the path of the extension or wing while channeling in the shank section of this type of insole. To this end United States Letters Patent No. 1,482,140, granted January 29, 1924 on the application of E. E. Orr, discloses a treadle-controlled adjustable edge gauge which is adapted to be adjusted to three positions to vary the width of feather and also to be moved to a fourth position where the gauge is lowered below the surface of the work support and out of the path of the extension. The edge gauge disclosed in that patent is provided with the customary limiting stops for indicating the three positions of the edge gauge used in channeling non-orthopedic insoles. These limiting stops arrest the movement of the edge gauge in three different positions and as a treadle transmits movement in only two directions, i. e., up and down, and hence is subject to only two limits or stops, the Orr machine is provided with two separate treadle mechanisms for operating the edge gauge. Inasmuch as many channeling machines now on the market are provided with several treadle mechanisms for controlling different elements of the machine, such for example, as the work support and the means for varying the length of the feed stroke of a selected knife, the addition of two more treadles creates a condition which is necessarily confusing to an operator.

It is an object of the present invention to provide an improved edge gauge operating mechanism which is simple and efficient in operation and in which a single control member is

utilized to adjust the gauge relatively to the cutting knives to regulate the width of the feather that is being cut by the knives and also to control automatically heightwise movement of the edge gauge with respect to the work upon movement of the edge gauge to a predetermined position of adjustment. As herein illustrated in a machine for channeling insoles, this invention may be recognized in the combination of a work support, an adjustable edge gauge located adjacent to the work support and arranged to overlie the work support in certain positions of adjustment and a manually operable control member which is adapted to adjust the edge gauge transversely to the line of feed, and also to control the heightwise movement of the edge gauge with respect to the work upon movement of the edge gauge to a predetermined position of adjustment.

With the above and other objects in view the invention will now be described with reference to the accompanying drawing and will be pointed out in the appended claims.

In the drawing,

Fig. 1 is a plan view of a portion of a channeling machine showing the improved edge gauge construction;

Fig. 2 is a view in elevation of the mechanism shown in Fig. 1 with the edge gauge in its lowered position wherein it is located below the surface of the work support; and

Fig. 3 is a view in elevation similar to Fig. 2 with certain parts broken away showing the edge gauge in its elevated position.

Referring to the drawing, the invention is shown as embodied in a machine of the type disclosed in United States Letters Patent No. 984,773, granted February 21, 1911 upon the application of W. C. Meyer. The illustrated machine comprises a rotary work support 10, a channeling knife 12 for cutting obliquely into the substance of an insole 14 so as to form a channel and an inner lip, an edge-slitting knife 16 for cutting inwardly from the edge of the insole in a plane parallel to the face of the sole to form an outer lip and a feather, and presser gauges 18 and 20 to limit the depth to which the knives enter the work. The machine is further provided with an adjustable slide 22 which is mounted in a guideway 24 located below the plane 10 of the table 10. The slide 22 has a laterally extending head portion 23 which has a groove therein in which is slidably mounted the depending shank 25 of an edge gauge 26. The edge gauge 26 is normally biased downwardly into engagement with the head 23, in which position it will be located below the surface of the work support, by a spring 28 which is connected at one end to the edge gauge 26 and at the other end to a pin 29 extending from the slide. The

slide 22 is moved relatively to the work support to move the gauge 26 transversely of the line of feed by a segmental gear 30 which meshes with gear teeth formed in the side of the slide 22, and 5 which is fast to the upper end of a rock shaft 32 journaled in a bracket 34. The lower end of the rock shaft 32 is connected to a crank arm 36 having a forked end which receives a block 38 pivoted to a rotatably mounted disk 40 having 10 a depending spindle which is journaled in a bracket 42. One extreme position of the gauge is determined by a pin 47 which is carried by the disk 40 and projects into a recess 43 in the bracket 42, and the other extreme position of the 15 gauge is determined by a pin 41 which also projects into the recess 43 and is carried by a collar 39 clamped to the disk 40. Connected to the lower end of the spindle is a hand lever 44 having a latch 45 thereon for determining the intermediate positions of the edge gauge by engagement with stops on the bracket 42 and a collar 37 clamped to the bracket 42. The latch 45 together with the pin 47 depending from the disk 40 and the pin 41 extending inwardly from the 20 collar 39 determine the various positions of the edge gauge in a manner similar to the corresponding latch 24 and pins 19 and 22 in United States Letters Patent No. 1,030,802, granted June 25, 1912, upon the application of F. E. 25 Bertrand, which shows a four position gauge adjusting mechanism for adjusting an edge gauge in a machine of the type disclosed in the patent to Meyer No. 984,773 referred to above. The brackets 34 and 42 are attached to a horizontal 30 projection 46 on the work support slide. Operation of the hand lever 44 rotates the disk 40 which in turn rotates the lever 36 and gear 30 to move the slide relatively to the work support 10.

40 The edge gauge is raised from an out of the way position below the surface of the work support where it is in engagement with the head 23 to an operating position above the surface of the work support by a lever 48 fulcrumed upon a pin 49 secured in the arm 36. The lever 48 has an end portion 51 which is disposed below the edge gauge shank 25 and is curved so as to underlie the shank throughout the range of movement of the arm 36. Formed upon the other end of the lever 48 at a locality adjacent to the disk 40 is a cam surface 53 which is adapted to be engaged by a cam surface 55 formed upon a cam plate 50 fast to a block 52 attached to the disk 40. Upon engagement of the cam surface 55 with the cam surface 53, the lever 48 is rotated in a clockwise direction about its pivot, as viewed in Fig. 3, raising the edge gauge above the surface of the work support. The cam plate 50 extends over that segment of the disk 40 which 50 corresponds to the positions of the gauge when regulating the channeling of regular insoles thus holding the gauge in its raised work engaging position throughout that range of movement but terminates short of the portion of the disk which corresponds to the position to which the edge gauge is moved by the lever 44 when a tab portion such as 15 of the illustrated insole is encountered, thus permitting the gauge to be moved downwardly under the urging of the spring 28 to enable the tab portion to pass over the gauge. 60

65 In channeling an orthopedic insole in the illustrated machine, the gauge 26 is adjusted to the three selected gauging positions in the usual manner by the lever 44 while the outer shank and ball portions are being operated upon. When 70

the tab portion is reached, the hand lever is moved to a fourth position, with the result that the cam plate is moved from above the lever 48 allowing the latter to tilt in a counterclockwise direction and the gauge 26 to drop below the level of the work support, thereby enabling the tab to pass over the gauge as the inner shank portion is channeled in the usual manner. 5

It is evident from the above description, that by placing the means for raising and lowering the edge gauge under the control of the hand lever which adjusts the edge gauge transversely of the line of feed, applicant has greatly simplified the control of the edge gauge, as in operating a machine equipped with an improved gauge mechanism built in accordance with the teachings of this application, all that an operator need do to control the gauge is to shift the conventional hand lever through the usual positions when channeling portions of an insole where the edge is not obstructed by a tab and when a tab portion is encountered, he need only move the hand lever to another position where the gauge will be automatically lowered out of the path of the tab permitting that portion of the insole 20 to be channeled. 25

Having thus described my invention, what I claim as new and desire to secure by Letters Patent of the United States is:

1. A machine for operating upon soles having, 30 in combination, a work support, an adjustable gauge adjacent to said support, means for adjusting said gauge relatively to the support, said means including a cam, and means controlled by said cam arranged to move the gauge to a 35 position below the surface of the work support at a predetermined position of adjustment of the gauge.

2. A machine for operating upon soles having, 40 in combination, a work support, an adjustable edge gauge adjacent to said support, means for urging the gauge in a downward direction toward a position below the surface of the work support, and means for adjusting said gauge relatively to the work support, said adjusting means 45 being arranged to maintain the gauge in its elevated position throughout a selected range of adjustment.

3. A sole fitting machine comprising a tool for operating on soles, a work support, a gauge, 50 a control member for adjusting said gauge relatively to said tool, and position indicating means for arresting the motion of the control member in three positions to indicate positions of the gauge relatively to the sole fitting means, said control member being arranged to control the movement of the gauge below the surface of the work support when shifted to a fourth position. 55

4. A sole fitting machine comprising a tool 60 for operating on soles, a work support, a gauge adjacent to said support arranged for movement transversely of the line of feed and also heightwise with respect to the plane of the surface of the work support, manually operable means for adjusting said gauge transversely of the line of feed, position indicating means cooperating with the manually operable means for indicating positions of adjustment of the gauge, and connections between the manually operable means and 65 the gauge for controlling the movement of said gauge heightwise with respect to the plane of the surface of the work support upon movement of the edge gauge to a predetermined position. 70

5. A sole fitting machine comprising a tool 75

for operating on soles, a work support, a gauge adjacent to said support, manually operable means for moving said gauge transversely of the line of feed, and means for moving said 5 gauge relatively to the plane of the surface of the work support, said last mentioned gauge moving means comprising connections between the edge gauge and the manually operable means arranged for operation by the manually operable means at a predetermined position of the 10 gauge.

6. A sole fitting machine comprising a work support, a knife, an adjustable gauge adapted to cooperate with the work and gauge the cut 15 made by the knife, manually operable means for moving the gauge transversely of the line of feed, said manually operable means being arranged for movement in a plane which is substantially parallel to the surface of the work 20 support, and means controlled by said manually operable means for depressing the gauge below the surface of the work support at a predetermined position of adjustment of the gauge.

7. A sole fitting machine having, in combination, a tool for operating on soles, a work support, a slide arranged for movement toward and away from the work support, an edge gauge mounted on the slide for movement heightwise with respect to the surface of the work support, 30 means for adjusting the slide relatively to the work support to move the gauge transversely of the line of feed, means for moving the edge gauge heightwise with respect to the surface of the work support to move it into and out of sole 35 gaging position, and manually operable means for operating the two aforesaid means, said manually operable means being constructed and arranged to operate the gauge moving means at a predetermined position of adjustment to cause 40 the heightwise movement of the gauge.

8. A sole fitting machine comprising a tool for operating on soles, a work support, an edge gauge support, an edge gauge vertically adjustable on said support, means for shifting said edge gauge 45 support relatively to the work support to move the gauge transversely of the line of feed, a shiftable member mounted on said means and arranged to move said edge gauge vertically on its support, and an operator-controlled means for 50 controlling the aforesaid shifting means and gauge controlling member.

9. A sole fitting machine for operating on orthopedic insoles comprising sole fitting means, a work support, an adjustable edge gauge support 55 adjacent to said work support, an edge gauge mounted on the edge gauge support for movement heightwise of the plane of the surface of the work support, resilient means for urging the edge gauge to a position below the surface 60 of the work support, a member for supporting the edge gauge in a raised position wherein the edge gauge is adapted to guide a work piece past the sole fitting means, and manually operable means for moving said edge gauge support relatively to the sole fitting means and arranged to 65 shift the gauge supporting member at a predetermined position of adjustment thereby to permit the depression of the edge gauge below the surface of the work support to permit an orthopedic extension on an insole to pass over the edge 70 gauge.

10. A sole fitting machine comprising sole fit-

ting means, a work support, an edge gauge support, an edge gauge adjustably mounted on the edge gauge support and arranged to overlie the work support in certain positions of adjustment, means for shifting said edge gauge support relatively to the work support, a member pivoted on the shifting means and arranged to move the edge gauge relatively to the plane of the surface of the work support, and an operator-actuated means for controlling the shifting means and gauge moving member, said operator-actuated means including a cam arranged to move said pivoted member at a predetermined position of adjustment of the edge gauge to control thereby the adjustment of the edge gauge relatively to 15 the surface of the work support.

11. A sole fitting machine comprising sole fitting means, a work support, an adjustable slide adjacent to the work support arranged slidably to receive an edge gauge, an edge gauge mounted 20 on said slide, means for moving said slide relatively to the sole fitting means, said means comprising a rotatable member and connections between the rotatable member and the slide arranged to move the slide upon rotation of the 25 rotatable member, a lever for shifting said gauge on the slide, and a cam on said rotatable member arranged to control said lever, said cam being proportioned and arranged to depress the lever in certain positions of adjustment of the 30 rotatable member to move the edge gauge to a work engaging position, and to be disengaged from the lever in other positions of the rotatable member to thereby enable the edge gauge to move below the surface of the work support. 35

12. A sole fitting machine for operating on orthopedic insoles comprising a knife for operating on soles, a work table for supporting a sole, a gauge engageable with the edge of a sole on said work table, mechanism for adjusting said gauge transversely of the line of feed to vary the gauged position of the sole on the work table, said mechanism comprising a rotatable member for moving the gauge toward and away from the knife, means for moving said gauge heightwise 45 of the surface of the work table, said means comprising a gauge shifting lever pivoted to the rotatable member and arranged to move said gauge in one direction and resilient means for normally urging the gauge in the opposite direction, 50 and a manually operable member for operating said gauge adjusting mechanism, said manually operable member including a cam for controlling the gauge shifting lever arranged to move the lever in one direction to hold the gauge 55 in one position of adjustment over a certain range of movement and upon movement of the gauge out of that range to release said gauge shifting lever to enable the spring to move the gauge to another position of adjustment. 60

13. Edge gauge mechanism for stock fitting machines comprising an edge gauge support, an edge gauge adjustably mounted on said support, a control system for shifting the support transversely of the line of feed, a separate independently operable control system for moving the edge gauge on its support, said separate control system including a gauge operating lever for moving the gauge heightwise of the support, and a manually operable control member for operating the two aforesaid control systems. 65
